FOUNTAIN PEN

William E. Houston, Columbia, S. C.

Application May 12, 1939, Serial No. 273,351

7 Claims. (Cl. 120—49)

The present invention relates to fountain pens and more particularly to improved cap means for protecting the pen point, which eliminates the necessity for the more or less awkward motions of one's hands when unscrewing the cap, reversing it and then placing it on the head end of the pen barrel in opening the pens as now in common use, and then reversing this procedure when closing the pen.

10 The primary object of the invention is to provide a closure cap for fountain pens, which is adapted to have a sliding movement over the pen barrel and which is readily locked in either an open or a closed position by a slight turn of the cap.

15 A further object resides in the novel arrangement for automatically opening and closing the lid of the cap as the cap is slid along the pen barrel.

20 A further object resides in the provision of a closure cap which may be slid from a closed position protecting the pen point, to an open position at the opposite or head end of the pen barrel when writing with the pen.

25 A further object is to provide a fountain pen embodying a reciprocating cap which may be moved along the pen barrel to a position remote from the pen point, well out of the way of the user's fingers and in a position to give better 30 balance and stability to movement of the pen when writing.

35 A still further object resides in the novel sliding cap arrangement whereby sufficient length to the pen is provided when the cap is slid to the head end of the barrel, and the lid of the cap so disposed as to not interfere with proper use of the pen.

40 Other objects and advantages of the invention will be apparent from the following detailed description, taken in connection with the accompanying drawing, forming a part of this specification and in which drawing:

45 Figure 1 is a view in side elevation of the improved fountain pen in a closed condition.

45 Figure 2 is a view showing the pen in use.

50 Figure 3 is a view showing the closure cap in its locked position over the head end of the pen barrel, the cap being shown in longitudinal section.

55 Figure 4 is a view taken at a right angle to the showing in Figure 3.

Figure 5 is an enlarged longitudinal section thru the cap in a closed position over the writing end of the pen barrel.

Figure 6 is a longitudinal section thru the cap detached from the pen barrel.

Figure 7 is an enlarged transverse section on line 7—7 of Figure 3.

Referring to the drawing in detail and wherein like reference characters designate corresponding parts throughout the several views, the improved fountain pen comprises a cylindrical barrel A having the sliding closure cap B reciprocally movable therealong to positions partially projecting beyond opposite ends of the barrel.

The barrel A comprises a plain surfaced body portion 10 provided at its forward or writing end with a slightly tapered and concaved removable head or grip 11 in the forward end of which is mounted the pen point 12. The rear flaring end of the grip 11 merges into the cylindrical surface of the barrel body portion 10. The pen barrel is of the self-filling type and has the usual ink sack 13 which may be collapsed by the filler lever 14 for allowing filling of the sack in the well known manner. As will be observed, the filler lever 14 is slightly offset radially from the back of the pen point 12.

The closure cap B comprises a tubular sleeve 15 having a snug but nice sliding fit over the barrel body portion 10. Closing the outer end of the sleeve 15 is a disc-shaped lid 16 which is hinged to close upon the end of the sleeve by means of a spring hinge 17 tensioned to normally close the lid upon the sleeve. One hinge leaf 18 of the spring hinge 17 is secured in any preferred manner to the edge of the lid 16, while the other hinge leaf 19 is secured to the sleeve 15 and extends longitudinally along the sleeve to form a clip 20 for retaining the pen in one's pocket.

A means is provided for automatically opening the lid 16 when the sleeve 15 is slid rearwardly on the barrel 10 so as to allow the pen point 12 to be projected without injury to the point. This means 40 comprises providing a longitudinal groove 21 in the inner side of the sleeve 15 which opens at the outer end of the sleeve and which at its inner end is inclined or beveled off as at 22 into the inner surface of the sleeve at a point spaced from the rear end of the sleeve. Adapted to extend longitudinally in this groove 21 is a small push rod 23 which is pivoted at its outer end as by a staple or the like 24 to the lid 16. Provided at the inner free end of the rod 23 to lie in the groove 21, 50 is a suitably rounded knob 25 having a diameter no greater than the depth of the groove 21, and which knob co-acts with the incline 22 for opening the lid 16 as the sleeve is slid rearwardly on the pen barrel. The groove 21 is provided in the 55

sleeve radially inward of the spring hinge 17, as will be readily observed.

When the cap B is closed over the pen point as in Figure 5, the lid 16 is held closed by the spring hinge 17 and is spaced from the tip of the pen point for a distance at least equal to the length of the inclined end 22 of the groove 21. As the sleeve 15 is slid rearward from its closed position as in Figure 5, the rounded knob 25 rides up the flaring surface of the grip 11 and engages the incline 22 which prevents the knob from at first moving along the pen barrel and exerts a thrust on the push rod 23 thus opening the lid 16 before it engages the pen point. As the sleeve is moved further, the knob is fully received in the groove 21 and may slide along the pen barrel to the open position of the sleeve as in Figure 3. It will also be observed in Figure 3 that the knob 25 so co-acts with the incline 22 and surface of the pen barrel as to hold the free edge of the lid 16 spaced slightly from contact with the pen barrel. This not only presents a better appearance but also prevents scratching the pen barrel by the lid.

Co-acting means between the barrel A and cap B is provided whereby the cap may be guided along the pen barrel and releasably held in either its closed position over the pen point or in its open position over the rear end of the barrel. Provided in the outer surface of the pen barrel 10 are two longitudinally extending parallel spaced apart guide slots 30 and 31 which are formed relatively narrow so as not to interfere with one's grip on the pen when being used. The guide slot 30 opens at the rear end of the barrel 10 and extends to a point closely adjacent the forward end of the barrel where it terminates in a diagonal locking slot 32, while the guide slot 31 opens at the forward end of the barrel and extends to a point closely adjacent the rear end of the barrel where it terminates in a diagonal locking slot 33 extending in an opposite direction circumferentially of the barrel to that of the locking slot 32. The guide slots 30 and 31 are spaced relatively close to one another and are provided on the pen barrel at a location approximately diametrically opposite to the groove 21 in the cap B. Projecting inwardly from the sleeve 15 at a point closer adjacent the forward end of the sleeve, and in substantially diametrical relation to the groove 21, is a guide stud 34 in the form of a rounded knob for sliding movement in the guide slot 31. This stud 34 may be formed integral with the sleeve 15. Projecting into the sleeve 15 at a point adjacent the rear end of the sleeve and slightly offset circumferentially from the stud 34 for a distance equal to the spacing of the guide slots is a second and removable guide stud 35 having a rounded knob for sliding in the guide slot 30. This stud 35 is threaded into the sleeve 15 to permit assembling of the sleeve with a limited sliding movement on the pen barrel.

The arrangement of guide slots and guide studs is such as to permit of the cap being locked in either position of movement by a slight relative turn of the sleeve on the pen barrel. As shown more clearly in Figure 7, the diagonal locking slots 32 and 33 gradually decrease in depth from their respective guide slots to the ends of the locking slots and form cam surfaces against which the guide studs bind for frictionally holding the cap and pen barrel against relative rotation when the cap is slid to position at either end of the barrel. When the cap

B is in a position covering the pen point 12, the stud 35 locks in the locking slot 32, and when the cap is in its open position at the rear end of the pen barrel, the stud 34 locks in the locking slot 33. 5

As will be observed, the spacing between the guide studs 34 and 35 is greater than the distance from the locking slots 32 and 33 from their respective adjacent ends of the pen barrel. Thus, when one stud is locked in its locking slot, the other stud is moved out of the end of its guide slot to permit relative rotary movement between the cap and pen barrel. 10

When opening the pen for use, the cap B is given a slight rotary movement which moves the guide stud out of the locking slot 32 and aligns the guide stud 34 with the open end of its guide slot 31. The cap is then slid rearward over the pen barrel and the rounded knob 25 on the push rod 23 co-acts with the inclined end 22 of the groove 21 to exert a push on the rod and open the lid 16 against the tension of the spring hinge 17 before the lid contacts the pen point 12. The cap may be slid along the pen barrel until the stud 34 reaches the rear end of the guide slot 31 and at which time the stud 35 will have moved out of the open end of its guide slot 30 to a point beyond the rear end of the pen barrel. A slight turn may then be given the cap for moving the stud 34 into the locking slot 33 and locking the cap in an open position. As seen from Figure 3, the knob 25 and the inclined or cam surface 22 are such as to hold the free edge of the lid 16 slightly spaced from the pen barrel. By having the filler lever 14 in offset relation to the back of the pen point, prevents the filler lever from interfering with sliding movement of the knob 25 along the surface of the pen barrel. 30

Referring particularly to Figure 2, showing the fountain pen in use, it will be seen that the stud and slot arrangement permits the cap to be moved to a position at the head end of the barrel and well out of the way of one's fingers when writing, with the cap resting between the juncture of the thumb and index finger. The lid 16 lays along the pen barrel in substantial alignment with the back of the pen point and therefore does not interfere with use of the pen. As shown in Figures 3 and 4, when the cap is slid rearward on the pen barrel, the cap extends for some distance beyond the rear end of the pen barrel and thus provides the desired length to the pen when writing. 40

Changes in detail may be made to the form of invention herein shown and described, without departing from the spirit of the invention or the scope of the following claims. 45

I claim:

1. In a fountain pen, a barrel having a pen point at its forward end, a sleeve slidable on the barrel, longitudinally spaced circumferentially offset studs on the sleeve co-acting with parallel longitudinal slots in the barrel for guided movement of the sleeve on the barrel, means limiting relative rotary movement between the barrel and sleeve when the sleeve is moved to either end of the barrel, a hinged lid closing the outer end of the sleeve, and means for causing the lid to be opened as the sleeve is slid rearward on the barrel. 60

2. A fountain pen comprising a pen holder including a barrel, a pair of parallel guide slots formed longitudinally of the barrel with one slot opening at one end of the barrel and the other 75

- slot opening at the opposite end of the barrel, a sleeve slidable on the barrel and having a pair of inwardly extending studs guided in said slots, a hinged lid for closing the forward end of the sleeve, and means for automatically opening the lid when the sleeve is slid rearward on the barrel. 5
3. A fountain pen comprising a barrel having a pen point at its forward end, a pair of parallel 10 guide slots formed longitudinally of the barrel, one of said slots opening at the forward end of the barrel and terminating in a locking slot adjacent the rear end of the barrel and the other slot opening at the rear end of the barrel and 15 terminating in a locking slot adjacent the forward end of the barrel, a closure cap for enclosing the pen point and including a sleeve slidable on the barrel, and a pair of guide studs extending inward from the sleeve for movement in said 20 guide slots, said studs being spaced apart longitudinally of the sleeve for a distance at least greater than the spacing of said locking slots from their adjacent ends of the barrel.
4. A fountain pen comprising a barrel, a guide 25 slot opening at the forward end of the barrel and closed at its rear end, a second guide slot parallel to the first slot and opening at the rear end of the barrel and closed at its forward end, a sleeve slidable on the barrel, a guide stud extending inward from the sleeve for movement in one of the guide slots, a removable guide stud 30 extending inward from the sleeve for movement in the other guide slot, one of said studs being movable past one end of the barrel and the other stud being movable past the other end of the barrel, a closure lid for one end of the sleeve, and 35 operating means for the lid.
5. A fountain pen comprising a barrel having an annular concaved grip at its forward end and 40 a pen point in the grip, a cap for enclosing the grip and pen point including a sleeve slidably guided on the barrel to limited positions of movement at opposite ends of the barrel, a hinged
- closure lid for the forward end of the sleeve, a longitudinal groove internally of the sleeve and opening at the forward end of the sleeve and having an inclined portion at its inner end, a push rod lying in the groove and pivoted at one end to the lid, and a rounded knob at the free end of the push rod lying in said concaved grip when the sleeve is enclosing the pen point, said knob co-acting with the concaved grip and said inclined groove portion for opening the lid as the cap is slid rearward on the pen barrel. 5
6. In combination with a fountain pen barrel having an annularly concaved grip at its forward end, a tubular sleeve slidable along the barrel from end to end thereof and having an internal groove, a spring hinged lid normally closing the forward end of the sleeve, and operating means within the sleeve including a push rod disposed in the groove and having a knob at one end co-acting with the concaved grip for opening the lid as the sleeve is slid rearward on the barrel, said operating means being movable into said groove of the sleeve to permit its movement along the pen barrel and said knob co-acting with the surface of the pen barrel and 20 the groove for holding the lid out of sliding contact with the barrel. 15
7. A sliding closure cap for writing instruments, comprising a tubular sleeve for sliding movement along the instrument, a lid for closing the forward end of the sleeve, a spring hinge for the lid and normally urging the lid to a closed position over the end of the sleeve, a groove internally of the sleeve and opening at the forward end of the sleeve and having an inclined cam portion at its inner end, a push rod fitting in the groove, means pivoting the push rod at one end to the lid, and a knob at the free end of the push rod and movable into the groove, said knob acting between the inclined 30 cam portion and the writing implement for opening the lid as the cap is slid on the implement. 35
